UNITED STATES PATENT OFFICE.

CHARLES ANDREW STURM, OF PORTLAND, OREGON.

STEAM-BOILER.

945,733.

Specification of Letters Patent. Patented Jan. 4, 1910.

Application filed August 19, 1908. Serial No. 449,192.

To all whom it may concern:

Be it known that I, CHARLES ANDREW STURM, a citizen of the United States, residing at Portland, in the county of Multnomah and State of Oregon, have invented 5 certain new and useful Improvements in Steam-Boilers, of which the following is a specification.

This invention relates to improvements in 10 steam boilers and has for its object to provide means for utilizing the heat from the burning fuel to the best advantage.

Another object is to provide such a boiler 15 which can be cheaply made and is simple in construction.

These objects are attained by means of the improvements illustrated in the accompanying drawings, in which—

Figure 1 is a sectional elevation. Fig. 2 20 is a sectional elevation on A—B. Fig. 3 shows a top view. Fig. 4 is a section on C—D. Fig. 5 shows a detailed sectional elevation of 9.

Like numerals throughout the several 25 views indicate similar parts.

Referring to the drawings, the boiler is shown inclosed by a brick casing 1 and metal front 13. The bottom compartment 19 having sides 2 and top 21 and bottom 20 30 is provided with an opening 3 surrounded by walls 18. A grate 4 is provided beneath opening 3 for the reception of fuel which is placed onto the grate through door 14. Compartment 19 is connected with an intermediate 35 compartment 9 extending from the front wall rearwardly and spaced from the rear wall of the inclosing casing, by pipes 5 and with another intermediate compartment 10 extending from the rear wall of the casing 40 forwardly and spaced from the front wall 13, by pipes 6. Compartment 10 is also connected with compartment 9 by pipes 7 and with compartment 11 by pipes 8. Compartments 9 and 11 are connected by pipes 22. 45 A steam dome 12 is connected with upper

compartment 11 by pipes 23. The smoke and heat from the fuel on grate 4 passes backward along the under side of compartment 9 and thence upward and forward along the under side of compartment 10 and 50 thence upward and backward along the under side of compartment 11 and finally out through stack 24. Water may be admitted in to the compartments by means of a pipe at any desired point. By arranging the 55 compartments and pipes as shown the water is allowed to circulate readily and steam will find its way easily toward the steam dome 12. Suitable handholes, gages, valves and other boiler accessories are provided where 60 needed.

What I claim is:

A steam boiler comprising a bottom chamber partially surrounding the fire box, an upper chamber connected with the steam 65 dome, a lower intermediate chamber extending from the front to a distance from the back, an upper intermediate chamber extending from the back to a distance from the front, a wall inclosing said chambers 70 and provided with an opening for the admission of fuel and an opening for the smoke and gases to flow out from between the upper, and upper intermediate chambers at the rear thereof, and pipes connecting 75 the front portion of the lower chamber with the lower intermediate chamber, the rear end of the lower chamber with the upper intermediate chamber, the rear end of the lower intermediate chamber with the upper 80 intermediate chamber, the front end of the lower intermediate chamber with the upper chamber, the upper intermediate chamber with the upper chamber.

In testimony whereof, I affix my signature 85 in presence of two witnesses.

CHARLES ANDREW STURM.
